TELEGRAPH SYSTEM

Arthur Tino Starr, Aldwych, London, England, assignor to Western Electric Company, Incorporated, New York, N. Y., a corporation of New York

Application December 27, 1930, Serial No. 505,075, and in Great Britain January 24, 1930.

15 Claims. (Cl. 178—66)

This invention relates to the electrical transmission of signals in code.

It applies to systems in which each signal element complies with one of two known voltage or current conditions. In D. C. telegraph systems this corresponds to systems in which two voltage or current values, for example, positive and negative, or positive and zero, etc., are used to transmit the intelligence. In carrier telegraph systems, (that is, where the signals are used to modulate a steady carrier frequency) the two conditions are in general, for example, full carrier and no carrier.

It has previously been suggested to transmit telegraph messages by a system analogous to that used for carrier wave telephony and known as single side band transmission, but the theory of the subject required that, for complete intelligence, the transmitted band should extend from 0 to s periods per second, where s is the dot frequency. From this it follows that after modulation the frequency nearest the carrier in each side band coincides with the carrier frequency. Consequently a filter with a perpendicular cut-off, which is not practicable, would be necessary in order to separate a side band from a carrier. As this is impossible in practice it becomes necessary to employ very expensive and elaborate phasing arrangements to cancel out frequencies of the unwanted side bands which would cause interference.

It is an object of this invention to overcome these disadvantages.

The various terms used throughout this specification will be defined as follows:

A unit of intelligence (that is, a letter or symbol) is made up of a number (say N) of signal elements occupying a total time T seconds.

A signal element is a given voltage or current persisting for a definite time called a time unit.

In the present invention, all time units are of equal duration. As the unit of intelligence contains N signal elements occupying a total time T seconds, a time unit is equal to T/N seconds.

The dot frequency is defined as a frequency equal to

$$\frac{N}{2T} \text{ pps.}$$

(Note—The speed in Bauds is equal to twice the dot frequency.)

A symbol required in the specification is denoted by N_t and is defined as follows. Assume a single signal element is transmitted, then the total time elapsing from the commencement of the received signal to the point where the current value becomes substantially negligible is N_t time units.

The signal frequencies may be defined as those which would be produced by the transmitter acting on a direct current source.

A feature of the invention is a telegraph system wherein the band of frequencies transmitted has a width numerically less than the dot frequency, but includes the dot frequency.

According to a further feature of the invention a telegraph system is provided wherein it is only necessary to transmit a band of signal frequencies of width

$$\frac{2}{N_t} s$$

to s where s is the dot frequency and N_t is as defined above.

One of the objects of the invention is to provide a carrier telegraph system in which the intelligence-bearing band of frequencies can be separated from the carrier and other frequencies by means of filters which permit of comparatively simple practical construction.

According to a further feature of the invention a carrier telegraph system is provided in which the carrier wave and one side band are completely suppressed and the intelligence-bearing band of width less than s are transmitted only.

According to a still further feature of the invention a telegraph system is provided wherein is transmitted along with the intelligence-bearing band nearest the carrier, a portion of unmodulated carrier.

The nature of the invention and other features thereof will be apparent from the following description taken in conjunction with the accompanying drawings of which Figs. 1, 2, 3 and 4 are descriptive of the theory underlying the invention.

Fig. 5 shows, in block form, one embodiment of the invention and Figs. 6 and 7 show similarly other embodiments. Fig. 8 illustrates the characteristics required for certain filters.

5 Heretofore it has been the accepted theory that it is necessary for complete intelligence to transmit the band of frequencies from 0 to s where s is the dot frequency. It will now be shown that, under certain conditions, it is not necessary to transmit such a wide band of frequencies.

10 Referring now to Fig. 1 of the accompanying drawings, (let us consider the signal $E(t)$ given by

$$15 \quad E(t) = 0, \quad t < t_1, \\ = E, \quad t_1 < t < t_2, \\ = 0, \quad t > t_2$$

20 This can be expressed as a Fourier integral as

$$E(t) = \frac{1}{\pi} \int dq \int_{-\infty}^{+\infty} E(\alpha) \cos \alpha(t - \alpha) d\alpha \quad (1) \\ 25 \quad = \int_0^{\infty} \phi(q) dq,$$

where

$$30 \quad \phi(q) = \frac{1}{\pi} \int_{-\infty}^{+\infty} E(\alpha) \cos q(\alpha - t) d\alpha \\ = \frac{2E}{\pi q} \sin q \left[\frac{t_2 - t_1}{2} \right] \cos q \left[t - \frac{(t_1 + t_2)}{2} \right] \quad (2)$$

Let

$$t_2 - t_1 = T/N$$

35 (that is, one time unit), then (1) becomes

$$E(t) = \int_0^{\infty} \frac{2E}{\pi q} \sin(qT/2N) \cos q \left[t - \frac{(t_1 + t_2)}{2} \right] dq \quad (3)$$

40 Equation (3) shows that we have here a continuous frequency spectrum of amplitude

$$S(q) = (2E/\pi q) \sin(qT/2N) \quad (4)$$

45 at a frequency $q/2\pi = f$ and phase

$$\theta = -(t_1 + t_2)/2 \quad (5)$$

The shape of $S(q)$ as a function of the frequency is shown in Fig. 2.

50 Let us now examine the value of $S(q)$ at various instants of time, remembering that $N/qT = s$

$S(q) = 0$ at $q = 2m\pi N/T$ except when $m = 0$, corresponding to $f = mN/T = 2ms$.

55 $S(q)$ is a maximum just before $(2m+1)s$, provided $m = 0$.

$$S(0) = (ET)/\pi N = \frac{E}{2\pi s}$$

$$60 \quad S(s) = (E/2\pi s) \times \frac{2}{\pi}$$

$$S(3s) = (E/2\pi s) \times \frac{2}{3\pi}$$

$$65 \quad S(5s) = (E/2\pi s) \times \frac{2}{5\pi},$$

etc.

Now suppose we have a signal as shown in Fig. 3, given by

$$70 \quad E(t) = 0, \quad t < 0, \\ = a_1, \quad 0 < t < T/N, \\ = a_2, \quad T/N < t < 2T/N, \\ = a_N, \quad (N-1)T/N < t < T.$$

Then by superposition of signals given by (3) we have

$$E(t) = (2/\pi) \int_0^{\infty} (1/q) \sin(qT/2N) \sum_{m=1}^{m=N} a_m \cos q [t - (m-1/2)T/N] dq \quad (6)$$

$$= \int_0^{\infty} \left[A(q) \cos q t + B(q) \sin q t \right] dq \quad (85)$$

where

$$A(q) = \frac{2}{\pi q} \sin(qT/2N) \sum_{m=1}^{m=N} [a_m \cos q(m-1/2)T/N] \quad (90)$$

$$B(q) = \frac{2}{\pi q} \sin(qT/2N) \sum_{m=1}^{m=N} [a_m \sin q(m-1/2)T/N] \quad (95)$$

The first factors in both expressions of (7) are identical form with $S(q)$ given in (4) and is the shape-factor for the D. C. wave. The second factors in the expressions are the discrimination factors and carry the intelligence conveyed by the signals; the shape-factor may be anything so long as it is known and does not vanish at any frequency at which we wish to know the discrimination factors. The discrimination factors may be taken as

$$C(q) = \sum_{m=1}^{N} [a_m \cos q(m-1/2)T/N] \quad (110) \\ S(q) = \sum_{m=1}^{N} [a_m \sin q(m-1/2)T/N] \quad (8)$$

Remembering that the speed of signaling is given by

$$s = N/2T \quad (9)$$

it is seen that $C(q)$ and $S(q)$ are repeated in frequency bands of width s bounded by odd and even multiples of s . It is therefore unnecessary to transmit a wider band than this. But on the other hand, theoretically it is not necessary to transmit such a wide band, because since Equation (6) above contains an infinity of frequencies in any finite band, however narrow, it would be sufficient to transmit any band, as narrow as we wish, and any such band will give us the whole of the intelligence. There are two drawbacks to this; first, the difficulty of extracting from a wave of such narrow frequency width the intelligence which it contains, and second, the interference of preceding and succeeding signals with the signal to be observed. The effect of preceding and succeeding signals is to lump the spectrum in the neighborhood of certain frequencies; the worst possible interference occurring when the preceding and succeeding signals are the same as the mid signal, in which case the lumping is complete at the frequencies given by the frequencies of the representative Fourier series. Everywhere else the amplitude falls to zero.

In this case it is necessary to take a finite frequency band of a certain minimum width at a proper part of the frequency spectrum.

The preceding theory as has been shown, deals with the infinite frequency spectrum, (that is the transients) produced by a single pulse as shown in Fig. 1. It is difficult to deal with an infinity of equations, and it is therefore preferable to work

with a steady-state signal, i. e. one which is repeated indefinitely.

It will now be shown how to transform the problem from a question of transient currents to one of steady-state signals.

It has been assumed that after N_t time units from the commencement of the received signal the current is substantially negligible. Then if we wish to consider the signal element occurring 10 in any time unit, we can assume that all signals transmitted N_t or more time units before it has no interfering effect on it. Hence these early signals may be replaced by whatever we like; so we choose them to be the same as those signals 15 in the N_t time units immediately before the considered signal indefinitely repeated. Thus we need only to consider a signal of N_t elements, indefinitely repeated.

If the signal similar to that shown in Fig. 3 20 but with N_t time units, is repeated indefinitely from $t = -\infty$ to $t = +\infty$ the function $E(t)$ can be expressed in a Fourier series, whose coefficients can be found by the ordinary method.

We find that

$$E(t) = 1/2A_0 + \sum_{m=1}^{\infty} A_m \cos(2\pi nt/T) + B_m \sin(2\pi nt/T), \quad (10)$$

where

$$\left. \begin{aligned} A_n - jB_n &= F(n) G_n - jS_n, \text{ where } j = \sqrt{-1} \\ F(n) &= 2N_t/\pi n \sin(n\pi/N_t), \\ C_n &= (1/N_t) \sum_{m=1}^{N_t} a_m \cos(2m-1)n\pi/N_t, \\ S_n &= (1/N_t) \sum_{m=1}^{N_t} a_m \sin(2m-1)n\pi/N_t \end{aligned} \right\} \quad (11)$$

40 The frequency corresponding to n is

$$\left. \begin{aligned} f(n) &= n/T = 2ns/N_t \\ \text{Hence also } n &= N_t f(n)/2s \end{aligned} \right\} \quad (12)$$

45 $F(n)$ is the shape-factor and is the same here as for the nonrepeated signal, excepting that here $F(n)$ exists only for discrete frequencies $2s/N_t$, $4s/N_t$, $6s/N_t$, etc., whereas before it existed for all frequencies, vanishing only at the frequencies 50 $2s$, $4s$, $6s$. It is therefore as though the continuous spectrum of the non-repeated signal has now become lumped at certain discrete frequencies, and has fallen away to zero everywhere else. It now remains to be seen which of these frequencies 55 need be transmitted to carry the signal without ambiguity or redundancy. For this we shall consider the case of a sequence signal when N ($=N_t$ at the moment) is odd, e. g. 5. It is reasonable to take N as a small number, and N_t is probably also small, and of the same order. By coincidence N_t is the same as the number of units in the Baudot code, but the reasoning is perfectly general.

From (11) and (12) above we see that

$$F(n) = (2N_t/n) \sin(n\pi/N_t),$$

and occurs at frequencies given by $f(n) = 2ns/N_t$. Therefore for $N_t = 5$, $f(n)$ takes the values $2s/5$, $4s/5$, $6s/5$, $8s/5$, $2s$, $12s/5$, etc. It is thus seen that the frequencies s , $3s$, $5s$, ... do not occur, whatever the shape-factor would have been. Also, as the shape-factor for a square wave vanishes at the frequencies $2s$, $4s$, $6s$, ... these frequencies 75 do not exist.

The discrimination factor is given by $C_n - jS_n$ where

$$\left. \begin{aligned} C_n &= 1/5a_1 \cos(n\pi/5) + a_2 \cos(3n\pi/5) \\ &+ a_3 \cos(5n\pi/5) + a_4 \cos(7n\pi/5) \\ &+ a_5 \cos(9n\pi/5) \end{aligned} \right\} \quad 80$$

and

$$\left. \begin{aligned} S_n &= 1/5a_1 \sin(n\pi/5) + a_2 \sin(3n\pi/5) \\ &+ a_3 \sin(5n\pi/5) + a_4 \sin(7n\pi/5) \\ &+ a_5 \sin(9n\pi/5) \end{aligned} \right\} \quad 85$$

It is seen that

$$\left. \begin{aligned} C_n + 5 &= -C_n, \\ S_n + 5 &= -S_n \end{aligned} \right\} \quad 90$$

$$C_0 = a_1 + a_2 + a_3 + a_4 + a_5 = -C_5 \quad 95$$

$$\left. \begin{aligned} C_1 &= a_1 \cos(\pi/5) - a_2 \cos(2\pi/5) - a_3 \\ &- a_4 \cos(2\pi/5) + a_5 \cos(\pi/5) = -C_4 \\ C_2 &= a_1 \cos(2\pi/5) - a_2 \cos(\pi/5) + a_3 \\ &- a_4 \cos(\pi/5) + a_5 \cos(2\pi/5) = -C_3 \end{aligned} \right\} \quad 95$$

$$S_0 = 0 = S_5$$

$$\left. \begin{aligned} S_1 &= a_1 \sin(\pi/5) + a_2 \sin(2\pi/5) - \\ &a_4 \sin(2\pi/5) - a_5 \sin(2\pi/5) = S_4 \end{aligned} \right\} \quad 100$$

$$\left. \begin{aligned} S_2 &= a_1 \sin(2\pi/5) - a_2 \sin(\pi/5) + a_4 \sin(\pi/5) \\ &- a_5 \sin(2\pi/5) = S_3 \end{aligned} \right\} \quad 100$$

Now as the shape-factor vanishes at the frequencies $2s$, $4s$, $6s$, etc., that is, at $n=5, 10, 15$, etc., we cannot determine Σa from any frequency but zero because Σa occurs only at $C_0 - C_5, +C_{10}, -C_{15}$, etc., and $C_5, C_{10},$ etc. occur at frequencies $2s$, $4s$, etc. at which the shape factor vanishes: also we see that the only other independent combinations of the a 's are S_1, S_2, C_1 and C_2 which can be found at various different frequencies, as shown by Equation (14) just given. Hence unless we transmit zero frequency we have not sufficient equations to determine the five a 's. This is the ordinary D. C. telegraph system, but in an ordinary practical two-current system the values of the a 's are known to be either one of the two current values. In effect, this is intelligence which needs no frequency spectrum to convey it, and we will therefore re-examine our equations in the light of this fact.

The only independent functions of the a 's are C_0, C_1, C_2, S_1, S_2 . C_0 is unique in that it never appears again, for it could appear only when $n=5, 10, 15, \dots$, and then the shape-factor vanishes. It contains the sum of the a 's. C_1, C_2, S_1, S_2 reoccur, the law of recurrence being given in Equation (14) above, and possess the property that they remain unaltered if the a 's are each increased by the same constant.

We can take the four equations given by C_1, C_2, S_1 and S_2 , except that a_1 is called a_1^1, a_2^1 etc. and add an arbitrary equation

$$a_1^1 + a_2^1 + a_3^1 + a_4^1 + a_5^1 = 0,$$

and solve for the a^1 's.

The values of a_1, a_2, a_3 etc. are clearly $a_1^1 + 1/5C_0, a_2^1 + 1/5C_0$, etc. for (1) these will 140 satisfy the Equations C_1, C_2, S_1, S_2 , since the a^1 's in them can be increased by a constant amount without altering their values, and (2)

$$\left. \begin{aligned} (a_1^1 + 1/5C_0) + a_2^1 + 1/5C_0 \\ + (a_5^1 + 1/5C_0) \\ = \Sigma a^1 + C_0 = C_0 \end{aligned} \right\} \quad 145$$

since we took $\Sigma a^1 = 0$.

So by taking C_1, C_2, S_1, S_2 and the arbitrary Equation $\Sigma a^1 = 0$ we get the values of the a 's ex- 150

cept for a constant. We could take $\Sigma a^i = K$ and we should then obtain the values less the constant $(1/5)(C_0 - K)$. If, for example, the a 's were $+1, +1, +1, -1, -1$, then C_1, C_2, S_1 and S_2 and $\Sigma a^i = 0$ would give values of a 's equal to $4/5, 4/5, 4/5, -6/5, -6/5$.

In a two-current system all that it is necessary to know is the difference between successive a 's as we know that they are either alike or unlike from the given conditions. In the numerical example just given it is seen that the difference between the successive a 's of the absolute signal, i. e. $+1, +1, +1, -1, -1$, are $0, 0, 2, 0$, which are clearly the same as the differences between successive values of the a 's of the signal, $4/5, 4/5, 4/5, -6/5, -6/5$. Therefore, assuming that a receiving instrument can be designed to operate on the change of value of the a 's it is clear that it is only necessary to transmit the two frequencies which carry C_1, C_2, S_1, S_2 . Such a receiving instrument may be, for example, a siphon recorder or an oscilloscope. In this example taken, frequencies $2s/5$ and $4s/5$ or $6s/5$ and $8s/5$ or $(2+2/5)s$ and $(2+4/5)s$, or in general $(2r+2/5)s$ and $(2r+4/5)s$ or $(2r+6/5)s$ and $(2r+8/5)s$ will suffice as shown in Fig. 4. These correspond to values of $n=1$ and $2, 3$ and $4, 6$ and 7 ($5r+1$) and $(5r+2)$, $(5r+3)$ and $(5r+4)$ respectively.

It appears, therefore, that it would be sufficient

30 to transmit a band such as $(\frac{2}{5}s \text{ to } \frac{4}{5}s)$ or $(\frac{6}{5}s \text{ to } \frac{8}{5}s)$, or $(2r+\frac{2}{5})s \text{ to } (2r+\frac{4}{5})s$ or $(2r+\frac{6}{5})s \text{ to } (2r+\frac{8}{5})s$,

35 where r is any integer.

It must be noted that it is not sufficient to transmit any two contiguous frequencies, for the contiguous frequencies $4s/5$ and $6s/5$ corresponding to $n=2$ and $n=3$, have the same discrimination factor associated with them and hence do not provide sufficient independent functions of the a 's to determine the a 's, except for the additive constant, of course.

Further consideration shows, however, that a peculiar property possessed by the frequency of the band nearer to the odd multiple of s modifies the band width required, in general, in order to convey the complete intelligence contained in any succession of signals.

50 This property will be explained in the following:

If a signal based on an N unit code is repeated indefinitely the steady state method developed above may be applied and it is found that the frequency band required depends naturally on N but also on whether N is odd or even. If N is odd the frequency s does not occur, as has been shown for $N=N_t=5$, and if N is even the frequency s does occur. By work analogous to that done for the case of $N=5$ it can be shown for example, that if $N=4$ the band needed is $(s/2 \text{ to } s)$; for $N=5$, the band is $(2s/5 \text{ to } 4s/5)$; for $N=6$, the band is $(s/3 \text{ to } s)$; $N=7$ the band is $(2s/7 \text{ to } 6s/7)$ etc. Obviously if N becomes large (infinite) the band width tends to become $(0 \text{ to } s)$ irrespective of N being odd or even.

The point of importance is, that when considering the lowest intelligence bearing band, the lower frequency of the band required continually diminishes as N increases, while the upper frequency oscillates to and from s with successively increasing integral values of N , but with diminishing divergence from s . Similar reasoning applies to all other bands.

75 Thus the important proposition may be stated

for the lowest band that the upper frequency required for the frequency band necessary is s and the lower frequency required is dependent entirely on the time, measured in time units, occupied by the total transients from a single signal element plus the signal element, i. e. N_t .

80 In the case of a laboratory experiment, it was found that the total pre and post transients associated with one signal element, plus the signal element, were contained for all practical purposes within a time equal to five time units. Hence the lower limit of the frequency band considered was $2s/5$.

85 If in another system this time was, say 6 signal elements, then the lower limit would be $90 (2/6)s = (s/3)$. The required band is therefore seen to be

$$\frac{2s}{N_t}$$

95 to s .

Fig. 5 shows a D. C. system in block form. The D. C. transmitter DCT_1 works at a dot frequency of s_1 , and uses a band width selected by the band pass filter BPF_1 ,

$$\frac{2s_1}{N_t}$$

100 to s_1 .

DCT_3 works at the same dot frequency but uses a band width of

$$\frac{2s_1 + 2s_2}{N_t}$$

105 to $3s_1$.

All the remaining odd channels use the dot frequency s_1 and band widths respectively $2s_1$ apart.

D. C. transmitter DCT_2 and all the even channels operate at a different dot frequency s_2 110 higher than s_1 to prevent coincidence of the edge of the required frequency bands, e. g. if $s_1 = s_2 = s$ channels 1 and 2 would coincide at the frequency s leading to confusion of the message.

Eventually, even with this difference between 115 s_1 and s_2 , as more channels are taken into use, the successive odd and even channels will get closer together and eventually over-lap. It was found that with practical filters a 6 channel system required the ratio of s_1 to s_2 to be approximately 23/27 in order to prevent too close spacing of the channels.

120 Channel 1 from DCT_1 to R_1 is more or less in the nature of a D. C. telegraph channel, but differs in that frequencies below

$$\frac{2s_1}{N_t}$$

125 need not be transmitted. The other channels, although sent by a D. C. transmitter, are more like carrier telegraph channels. There is a consequent saving, for only one modulator is needed to send these channels, whereas in ordinary carrier telegraphy a modulator is needed at the sending of the channels.

130 However, frequency-translating devices, i. e. de-modulators D_2 and D_3 etc., are needed in channels 2, 3 etc., at the receiving end as shown. The correcting networks CN_1, CN_2, CN_3 apply both attenuation and phase shift adjustments in 135 known manner, to give the desired received wave.

140 In the above reasoning it has been assumed that all that is required is the difference between the voltages associated with successive signal elements and not their absolute values. This is satisfactory in double-current D. C. systems and carrier systems as the voltage associated with each time unit is known to be either +1 or -1 (or, on or off) respectively, and this amounts to a foreknowledge of some of the conditions of the 145

transmission which does not need line time for transmission.

It can be shown that when an A. C. source is switched on to and off from the line in the same way as a D. C. source, then if the A. C. source is of a sufficiently high frequency, the shape-factor of the resulting wave, assumed indefinitely repeated or non-repeated, is the same as the shape-factor for the direct current case shifted to the right in the frequency spectrum by an amount equal to the frequency of the A. C. source, and therefore the analysis of the D. C. case applies here. If the carrier frequency is not high compared with the dot frequency, the shape-factor is not the same as for the D. C. case, but the discrimination-factors will be the same, and the theorem as regards the band width necessary to transmit complete intelligence will follow in the same way. Hence as the lowest frequency required is displaced from the carrier frequency by a definite amount, it is now possible to select the "single side band" frequency spectrum, this band width being the same as for the D. C. case, i. e.

25

 $\frac{2s}{N_t}$

to s but with a location in some part of the frequency spectrum depending on the carrier frequency.

Fig. 6 shows how this may be carried out. Instead of passing channels 1, 2, 3, etc., directly out on to the line, they can be passed in to a modulator of a certain carrier frequency f_c and translated up in the frequency spectrum by a frequency f_c . It is now comparatively easy to transmit a single side band for each channel, because the intelligence bearing bands are separated from the carrier frequency, which can thus be easily suppressed. In Fig. 6 it will be assumed that it is required to transmit the upper side band. The D. C. transmitter DCT supplies signals to the band pass filter BPFa which selects a band of the corresponding width from

45

 $\frac{2s}{N_t}$

to s , and passes this band on to the modulator M supplied with a carrier frequency f_c . The band pass filter BPFb selects a side band

$$f_c + \frac{2s}{N_t} \text{ to } f_c + s$$

and transmits it to the line L. At the receiver the incoming frequency band passes through a similar band pass filter BPFc and the passed band is de-modulated (i. e. translated down in the frequency spectrum) in the de-modulator DW supplied with a frequency f_c . The output from the demodulator passes through a band pass filter BPFd which selects the desired band of

50

 $\frac{2s}{N_t}$

to s , which after passing through the correcting network CN which supplies the necessary attenuation and phase adjustment, is applied to the receiver R.

A better method than the scheme of Fig. 6 is to make the signal modulate the carrier directly and thereupon filter out the required side band and pass this band to the line without the intervention of a modulator. The advantages of this scheme are as follows: One filter is saved per sending channel. The harmonics of the D. C. wave are not formed, as they would be in the

modulator method. Also, attenuation and phase shift due to the modulator are avoided.

An alternative method of transmission consists in sending a separate message in each of the side bands of a single carrier with a portion of unmodulated carrier transmitted in addition to the side bands.

Referring now to Fig. 7, O is an oscillator which provides the necessary carrier frequency. This is fed into two transmitters T1 and T2 and also into the line L direct through the band pass filter BPF. BPF1' lets through the lower side band and BPF2' the upper side band. Phase shifters PS1 and PS2 serve the purpose of correcting the changes (at different frequencies) due to the band pass filters. Thus it will be seen that a portion of unmodulated carrier and two separate side bands carrying different messages are fed into the line. At the receiving end each of the band pass filters BPF3 and BPF4 lets through one side band with a part of the unmodulated carrier. Each side band is adjusted for attenuation and phase shift due to the line and band pass filters BPF3' and BPF4', this being provided for in equalizers E3 and E4 and phase shifters PS3 and PS4. Each signal is now demodulated by the appropriate detector D3 or D4 and the resulting currents operate the receiving mechanism R3 and R4 to record the signals. The receiver, as in the case of the preceding examples, may be any suitable telegraph receiver, for example, a siphon recorder, tele-printer recording oscilloscope, or any sensitive recorder.

In order to minimize interference between the channels but at the same time to receive as large a carrier as possible, for obtaining as strong a signal for demodulation purposes as possible, the sending filters BPF1' and BPF2' should have attenuation characteristics as shown in Fig. 8 since the form of the characteristics of BPF1' and BPF2' are such as to minimize interference between the channels and the forms of the characteristics of BPF3' and BPF4' are such as to separate the bands and let through a moderately large portion of the carrier to each channel.

Although I have described certain methods of carrying the present invention into effect, it is to be understood that other modes of applying the principles set forth above will be immediately apparent to those skilled in the art, and I do not, therefore, limit myself to the precise embodiments described above.

In the claims, the word "multiple" is used in the generic sense to include single as well as plural multiples, e. g., the expression "multiple of the dot frequency" may include the dot frequency itself.

What is claimed is:

1. A telegraph system comprising means for causing each signal element to comply with one of two known electrical conditions that are used to transmit the intelligence, and frequency selective means for selecting from the signalling waves, for transmission, frequencies of a band which has width numerically smaller than the dot frequency, and which, in its normal position in the frequency spectrum, has an odd integral multiple of the dot frequency as one of the boundaries of the signal frequencies.

2. A telegraph system comprising means for creating waves representing signal elements each of which complies with one of two known electrical conditions that are used to transmit the intelligence, and frequency selective means for se-

lecting from the signaling waves, for transmission, frequencies of a band which has band width

$$s \cdot \frac{N_t - 2}{N_t},$$

5 and which in its normal position in the frequency spectrum, has an odd integral multiple of s as one of its boundaries, where s is the dot frequency and N_t is a number as defined in the specification.

10 3. A telegraph system as claimed in claim 2, comprising frequency-translating means for transferring to a given position in the frequency spectrum a frequency band as specified in claim 2.

15 4. A telegraph system as claimed in claim 1, with receiving means for extracting the intelligence from the limited band of signal frequencies transmitted.

20 5. A direct current telegraph system comprising message channels and frequency selective means in said channels for selecting for transmission in the respective channels respective frequency bands of width

$$25 s \cdot \frac{N_t - 2}{N_t}$$

spaced throughout the frequency spectrum so that successive bands include successive odd integral multiples of s , where s is the dot frequency and N_t is a number as defined in the specification.

30 6. A direct current telegraph system as claimed in claim 5, comprising means for producing a different dot frequency for every channel.

35 7. A telegraph system comprising a group of message channels and a group of direct current telegraph transmitters therefor of one dot frequency, a second group of message channels and a second group of direct current telegraph transmitters therefor having a higher dot frequency, frequency selective means in said first channel group selecting from the signal waves in its channels, for transmission in the respective channels of that group, frequency bands each of width numerically smaller than the dot frequency for that channel group and each with an odd integral multiple of that dot frequency as a limiting frequency, and frequency selective means in said second channel group for selecting from the signal waves in its channels, for transmission in the respective channels of that group, frequency bands alternating in order in the frequency scale with said first mentioned frequency bands and each of width numerically smaller than the dot frequency for the second channel group and each with an odd integral multiple of that dot frequency as a limiting frequency.

40 8. A telegraph system comprising a transmission line, a plurality of direct current telegraph transmitters, band-pass filters respectively connecting said transmitters to said line, each filter passing a frequency band lying in a different portion of the frequency spectrum and having a band width numerically smaller than the dot frequency of its transmitter, and signal receiving means connected to said line and comprising signal receiving channels, filters corresponding respectively to said first mentioned filters connected in said receiving channels respectively, and frequency translating means connected in

each of said receiving channels other than the lowest frequency channel.

9. A carrier wave telegraph transmitting system comprising a carrier wave transmission circuit, a source of carrier telegraph signaling waves, and frequency selective means connecting said source to said circuit for selecting from said signaling waves, for transmission to said circuit, frequencies of a band which has width numerically less than the dot frequency and which has as one of its limiting frequencies a frequency algebraically differing from the carrier frequency by an odd integral multiple of the dot frequency.

10 10. A carrier wave telegraph system as claimed in claim 9, in which the width of the frequency band is

$$s \cdot \frac{N_t - 2}{N_t},$$

where N_t is a number as defined in the specification and s is the dot frequency.

11 11. A carrier wave telegraph transmitting system comprising means for producing two different carrier telegraph messages having the same carrier frequency and occupying frequency ranges on either side of the carrier frequency, a carrier telegraph transmission circuit, and filters connecting said means to said circuit for selecting from said messages, for transmission to said circuit respective groups above and of frequencies of bands spaced respectively below the carrier frequency and each having a width of

$$s \cdot \frac{N_t - 2}{N_t}$$

12. A system comprising means for producing carrier telegraph signal waves, a carrier telegraph transmission circuit, frequency selective means for selecting from said signaling waves, for transmission to said circuit, frequencies of a band which has width numerically smaller than the dot frequency and which has as one of its limiting frequencies a frequency algebraically differing from the carrier frequency by an odd integral multiple of the dot frequency, and means for transmitting waves of the carrier frequency to said circuit.

13. The method which comprises transmitting direct current telegraph signals as a band of frequencies that has width numerically smaller than the dot frequency and that has an odd integral multiple of the dot frequency as one of the boundaries of the signal frequencies.

14. The method which comprises transmitting carrier wave telegraph signals as a band of frequencies that has width numerically smaller than the dot frequency and that has an odd integral multiple of the dot frequency as one of the boundaries of the signal frequencies.

15. The method of transmitting signals in code which comprises transmitting each of the signal elements in compliance with either of two electrical conditions either of which they are known to fulfill, and transmitting each of the signal elements as wave components embraced in the same frequency band having width numerically smaller than the dot frequency and having an odd integral multiple of the dot frequency as one limiting frequency.
